UNITED STATES PATENT OFFICE.

OTTO KARTZMARK, OF NEW HAVEN, CONNECTICUT.

LOCKED SURFACE PIN.

1,371,901.

Specification of Letters Patent. Patented Mar. 15, 1921.

Application filed October 24, 1919. Serial No. 332,887.

To all whom it may concern:

Be it known that I, OTTO KARTZMARK, a citizen of the United States, and a resident of New Haven, in the county of New Haven and State of Connecticut, have invented a new and Improved Locked Surface Pin, of which the following is a full, clear, and exact description.

This invention relates to buckles or clasps and has particular reference to pins or buckles adapted to be detachably secured directly to the surface of a garment, fabric or the like with an action somewhat similar to that of a cat's claws.

Another object of the invention is to provide a pin for easy attachment to or removal from the surface of a garment or fabric, the manipulation of the pin being readily effected by one hand, and after the device is attached it occupies but a minimum amount of room and is consequently neat in appearance and comfortable to the person.

A still further object of the invention is to provide an improved pin or clasp for the attachment of elastic straps, hangers, or the like, for sleeve or hose supporters or other analogous uses.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan or face view of one adaptation of my invention shown attached to two different garments or two remote portions of the same garment.

Fig. 2 is an enlarged longitudinal section on the line 2—2 of Fig. 1.

Fig. 3 is a horizontal section on the line 3—3 of Fig. 2.

Fig. 4 is a similar view on the line 4—4 of Fig. 2.

Fig. 5 is a sectional detail on the line 5—5 of Fig. 3.

Figs. 6 and 7 are plan views of the blanks for the bodies or shells of the pins of Figs. 3 and 4 respectively.

Referring now more specifically to the drawings I show my invention as comprising

two pins 10 and 10' connected by a strap 11 which is preferably of elastic webbing or the like but which *per se* has no particular bearing upon my improvement which relates to the form of the pin or clasp. In other words so far as the strap 11 is concerned any other sort or type of means might be attached to either of the pins. This illustration, however, is adopted as suitable for illustrating the utility of my improvement as a sleeve or hose supporter.

The pin 10 comprises a shell or body 12 formed preferably from a single blank of sheet material such as a good quality of tin or the like stamped in the form shown in Fig. 6 and provided with integral bearing ears 13 at the ends of the body, each having a bearing hole 14. Between the ends are provided a pair of spaced slots 15 the main portions of which are parallel to each other and extend across the longitudinal center of the body while the outer ends thereof are bent laterally forming shoulders 16. Along the side of the body opposite the shoulders 16 is formed a bar 17 as by slitting the blank at 18 and bending the metal outward forming a rounded edge over which the webbing or the like is looped at 11' whereby the tendency for the sheet material of which the body is made to cut the webbing is reduced to a minimum. The blank thus formed is then cupped or dished on what becomes the inner side as shown plainly in Fig. 2 so as to constitute a housing for the movable claw members and the ears 13 are bent inward so as to lie adjacent to the end portions of the flange constituting the rim of the body. (See Fig. 5.) Said rim is unbroken at these parts and the position of the ears adapts them in a peculiar manner as bearings as will appear presently.

In the pin 10 I show a claw device comprising an axle 19 in which are fitted rigidly a plurality of spaced claws 20 and 21. Obviously in practice I do not propose to be limited to any particular number, arrangement or design of these claws, but in my experience I have found the use of four, or two of each kind, is very satisfactory. The claws 20 might be described as being made from headed pins, the portion of each intermediate the head and the point being bent at two angles at 22 and 23, the portion 24 between the angles coinciding with the axis of the axle 19 while the portions lead-

ing outward from said axle emerge from the axle on diametrically opposite sides or approximately so. The portion 25 of each of these claws 20 may be regarded as a finger piece and operates in a slot 15. The angle at 22 is slightly greater than a right angle so that the normal tendency of the finger piece portion 25 is to spring laterally so as to snap behind the shoulder 16 when the pin 5 or clasp is set and whereby the claws are locked from movement from closed to open position. The point or prong portion of each of the claws is bent to approximate a semi-circle so that when the pin is open as 10 indicated in dotted lines in Fig. 2 the points of the prongs will readily grasp into a garment or fabric, the finger pieces at this time being against the closed inner ends of the slots 15 preventing the swinging of the 15 prongs too far around their axis. After the points are thus engaged with the garment or fabric a slight pressure from the operator's fingers upon the body 12 thereof will bring it directly into firm contact with the 20 surface of the garment and while the pin is thus held the operator will bear upon the finger pieces and swing them around into flat position, as in Fig. 2, causing thereby the 25 points of the prongs to project twice through the fabric, once through the holes entered first by the points at 26, and secondly through the holes 27. The points of the prongs at this time will come close to the 30 inner surface of the body or shell 12, and with the finger pieces locked behind the shoulders 16 where they are held temporarily 35 due to the resiliency of the pin members there is no possibility for the device to be inadvertently or accidentally detached from 40 the garment. I wish to call in this connection particular attention to the fact that the strain brought to bear upon the device as a result of a pull upon the strap 11, or its equivalent, applied to the bar 17 is resisted 45 by the garment G at two spaced points for each prong and moreover such strain upon the fabric tends to draw it away from the points of the prongs and toward the axle, whereas in the usual types of buckles with 50 which I am familiar the tendency is for the garment or fabric to be drawn toward the points of the pins or prongs. It is to be noted also that after the device is attached as shown the points of the prongs are well 55 guarded both from damage to themselves and injury to the person, and the device as a whole presents a flat, neat appearance and possesses maximum strength.

The two claws 20 are those which have the 60 finger pieces 25 and they are so arranged with respect to the slots 15 and shoulders as to facilitate the release of the device in the easiest manner, that is to say to release the device from the garment the operator 65 presses the outer or headed ends of the mem-

bers toward each other between his thumb and finger causing the releasing simultaneously thereof from the shoulders and the subsequent swinging thereof back to open position. This manual movement of the 70 claws causes the direct release of the prongs from the garment with the least possible likelihood of breaking any of the threads of the garment.

The pins or claws 21 serve exactly the 75 same manner as the others for the coöperation with the garment, but these pins are bent at 30 forming in addition to the prongs only straight axial portions 31 which project beyond the axle 19 for coöperation with the 80 holes 14 of the ears 13 as bearings. With the body formed as above described and with the ears 13 bent inward the claw and axle portion will then be inserted as a unit, one trunnion 31 being slipped first into one of 85 the holes 14 and then the other trunnion will be snapped into the other hole 14 making not only a positive and permanent attachment means for the axle and claws but also a construction in which the exterior of the pin 90 as a whole is neat, smooth and unbroken.

The pin 10' differs but slightly from pin 10, the body 12' thereof being the same as the other except that a single slot 15' is provided at the longitudinal center of the body 95 but wide enough to accommodate two claws together, and the shoulders 16' are formed at the outer end of the same slot, but their function is exactly the same as above described. The axle 19' is substantially the 100 same as the axle 19 but the prongs 20' are bent toward each other at 23' instead of in the opposite direction so that the finger piece portions 25' thereof lie and operate in close proximity to each other in the slot 15'. 105 The prongs 21 are shown as being the same as already set forth and with their trunnion portions 31 coöperating with the bearing ears 13. The manipulation of this pin is practically the same as already set forth. 110

I claim:

1. In a device of the class set forth, a pin comprising a body, a claw member pivoted therein and hanger means attached to the body, the prong portion of the claw means being projectable through a garment or fabric toward the hanger means, and means integral with the claw member to lock the claw member from movement. 115

2. The herein described pin comprising a hollow body, claw means journaled within the body and comprising a plurality of prongs extendible through a garment toward one side of the body, and draft means attached to the body adjacent to the points of 120 the prongs. 125

3. In a pin of the class set forth, the combination of a body, a claw device journaled within the body and including a plurality of prongs of circular arc shape, the points of 130

the prongs being movable through a fabric each at two spaced portions, means to lock the claw device from movement, and draft means attached to the body and tending to cause the fabric to be drawn toward the axis of the claw device.

4. In a surface pin, the combination of a body slotted from one side across the longer axis thereof, a claw journaled within the body, said claw comprising a prong and means to move the prong around the axis of the claw, said moving means including a member movable along the slot aforesaid, and means to lock the movable means from movement from locked position.

5. In a surface pin, the combination of a slotted body, a claw journaled within the body and having one or more arc shaped prongs adapted to be projected through a fabric and finger means movable along the slotted portion of the body to cause the projection of the points through the fabric, and a pair of spaced shoulders through which the finger means coöperates to lock the claw in holding position.

6. In a device of the class set forth, the

combination with a hollow body, an axle journaled therein and a plurality of prongs connected to the axle, two of said prongs serving as trunnions for the axle, and finger pieces for manipulating the prongs extending from the remaining prongs and coöperating with the body, substantially as set forth.

7. In a device of the class set forth, the combination of a body, an axle journaled therein, and a plurality of prongs fixed to the axle and projecting from opposite sides thereof, each of the prongs projecting from the axle at different distances from the ends of the axle, one end of each prong being sharpened and the other constituting a finger piece for manipulation and locking thereof.

8. In a device of the class set forth, the combination of a sheet metal body having a concavity on one side and a pair of end ears integral therewith, said ears being formed with bearing holes and extending inward to lie within the body, and prong means having end trunnions snapped into said ears.

OTTO KARTZMARK.
